IMPULSE VOLTAGE DEVICE

Willem Hondius Boldingh, Eindhoven, Netherlands, assignor to Hartford National Bank and Trust Company, Hartford, Conn., as trustee

Application July 8, 1946, Serial No. 681,909
In the Netherlands March 22, 1943

Section 1, Public Law 690, August 8, 1946
Patent expires March 22, 1963

6 Claims. (Cl. 171—97)

1

Impulse voltage devices consist of a plurality of condensers which are connected in parallel through the intermediary of resistances and in series through the intermediary of spark gaps. The condensers are charged by a source of direct current. At a determined voltage the spark gaps break down and the charge of the condenser flows away through a resistance.

Devices of this type are usually very bulky so that they take up much room.

During the charge the successive condensers acquire a steadily increasing voltage with respect to earth. For this reason one has proceeded to mount the condensers in metal cases and to arrange the latter in stages on an insulating base so that the insulation resistance increases in accordance with the voltage of the condensers relatively to earth.

In another form of construction the condensers are provided with an insulating envelope, owing to which they could act at the same time as supporting constructional elements. For impulse voltage devices of high power the condensers are sometimes distributed over more than one, for example, four columns. By the interposition of insulators, for example, a helical structure is obtained in this case. In view of a satisfactory spatial potential distribution and of a practical construction the condensers are arranged in the various columns at an equally higher level with respect to the condensers which precede in the circuit arrangement, the resistances and the spark gaps being housed in the space bounded by the columns.

It has also been proposed already to superpose all the condensers on one another in a common envelope consisting of insulating material, owing to which a column-shaped structure is obtained. This construction requires a comparatively large base but the height of the column increases with the voltage. The consequence thereof is, that the voltage which can be generated with the aid of this installation is limited by the rigidity of the column, which is insufficient in the case of a large height. In this known device each condenser consists of a plurality of disc-shaped elementary condensers which are connected in series.

These elementary condensers are superposed on one another in the required number so that they form a unit wherein the connecting terminals are located on the two terminal faces. The arrangement in the column is such that the potential difference across the condensers occurs

2

during the process of charging in the direction of the axis of the column.

This form of construction has the drawback that the constructional height of the column must be larger than is required in view of the dimensions of the condensers, for the dimensions of the column in the direction of the length, i. e. the height of the installation, are not only determined by the height and the number of the condensers utilized. Two successive condensers, which are superposed on one another in the column, must be separated from one another by an insulating layer, which is calculated for the direct-current voltage up to which the condensers are charged. The constructional height required for each condenser consequently becomes twice as large as would be necessary in view of the insulation length required for the charging voltage.

The present invention has for its object to make in such an impulse voltage device which comprises condensers which are connected in parallel through the intermediary of resistances and in series through the intermediary of spark gaps, a more efficient use of the room available in the column. It is thus achieved that with the same height of the installation use may be made of a larger number of condensers and that consequently the impulse voltage may be accordingly higher.

According to the invention, use is made of two or more than two condensers which are arranged in the column in such manner that the potential differences brought about by the application of the charging voltage, substantially occur in the transverse direction and that those points of the condensers which are located in the column above one another in the axial direction have during the charging process of the condensers equal or substantially equal potentials. Each condenser may consist in this case of elementary condensers which have been united so as to form a stack or of a plurality of such stacks, which are located parallel to one another, whilst the condensers are arranged in the column in such manner that the direction in which the potential difference across the condensers occurs during the charging period is perpendicular to the axis of the column and the corresponding connecting terminals of the various condensers are located in the axial direction above one another. With this arrangement of the condensers all points which have equal or substantially equal potentials during the charging period are located in the same plane. Owing to the fact that during the charging of the condensers there occurs substantially no po-

tential difference in the axial direction of the column, it is not necessary that the spacing which must be maintained between the successive condensers should be calculated for the direct-current voltage to be applied. The larger proportion of the available height may therefore be taken up by the condensers since the insulation between the latter should only be able to sustain impulse voltage loading for which a much smaller insulation distance is sufficient.

A very advantageous form of construction is obtained if each condenser is placed in a case and the separate cases are united to form a column. If there occurs a fault due to deterioration of one of the condensers, this condenser can easily be replaced by another. It is only necessary to substitute a new condenser case for the faulty part.

The invention will be explained more fully with reference to the accompanying drawing wherein

Fig. 1 represents the known device, wherein use is made of large flat condensers and

Fig. 2 represents diagrammatically, by way of example, a device according to the invention.

In the device according to Fig. 1 the condensers are surrounded by a cylindrical envelope 1 of insulating material which is arranged on a base-plate 2. In the example shown the column comprises five stages of the impulse voltage device according to the system of connections of Marx. If desired, this number may be taken larger or smaller so far as such is admissible in view of the stability of the column. The use of a plurality of stages increases the drawback that, if any of the condensers gets out of order, the entire column has to be taken to pieces or to be replaced by a new one. The column is provided with a ring 3 which has a large surface area in order to reduce the risk of flashing-over along the surface of the column during the discharge of the condensers.

The condensers 4 as well as the charging resistances 5 and the spark gaps 6 are diagrammatically represented.

As may be seen from the figure, the mounting height of each stage is determined by twice the direct-current voltage for charging the condensers, i. e. once for the height of the condensers between the points a_1 and b_1 , a_2 and b_2 , a_3 and b_3 , etc. and once for the insulation between the separate condensers that is to say between the points b_1 and a_2 , b_2 and a_3 , b_3 and a_4 , etc. In principle only half of the height is available for the condensers.

The loading with direct-current voltage requires a much greater insulation length than the loading exclusively with impulse voltage, so that with the device according to the invention and with the same mounting height the room available for housing the condensers is much larger, as may be seen from Fig. 2. This figure shows, likewise diagrammatically, the arrangement of the condensers 4, the resistances 5 and the spark gaps 6. The device consists of separate units. Each unit consists of a case 7 which comprises a bottom 8 and which is made of insulating material, and contains a condenser. As appears from the drawing, the voltage increases from the points a towards the points b , i. e. in the transverse direction. The whole of the diameter of the column is available for the insulation between the two connecting terminals of each condenser. The points which have the same potential during the charging of the condensers are located perpendicularly above one another, so that substantially no loading with direct-current voltage does occur between the various cross-sections in the axial

direction of the column. The insulation distance between the condensers is consequently determined by the impulse voltage and may be appreciably smaller than if there occurs a similar loading of the insulation distance with direct-current voltage.

The cases 7 are provided with flanges 9 of insulating material, which serve for the attachment of the resistances 5 and the spark gaps 6 which 10 are arranged outside the cases, a compact unit of the smallest possible dimensions being thus obtained.

The units may be mounted and taken to pieces in a simple manner, so that it is easily possible to 15 arrange the generator at another place and, in the case of disturbances, to eliminate the fault by replacing the faulty unit by a fresh one.

The condenser present in each unit is built up from one or more stacks which consist of a plurality of elementary condensers connected in 20 series. The various stacks are connected in parallel, which gives rise to the production of the surfaces of equal potential. The units must be arranged in the column relatively to one another in such manner that the corresponding equipotential surfaces form part of a common potential surface, owing to which no potential differences or only slight potential differences are produced during the charging of the condensers in the direction 25 of the length of the column.

What I claim is:

1. An impulse generator adapted for energization by a direct-current source, said generator comprising an insulating column, a plurality of 35 condensers each constituted by a pair of parallel plates, said condensers being colinearly arranged at spaced positions in the axial direction within said column, each set of corresponding plates of said condensers being aligned in a plane parallel to said axial direction, first resistance means external to said column and interconnecting the corresponding plates in one of said sets, second resistance means interconnecting the corresponding plates in the other of said sets whereby said condensers are connected in parallel relation through said resistance means, and spark gap means external to said column and arranged to connect said condensers in series relation.

2. An impulse generator adapted for energization by a direct-current source, said generator comprising an insulating column, a plurality of 50 condensers each constituted by a pair of parallel plates, said condensers being colinearly arranged at spaced positions in the axial direction within said column, each set of corresponding plates of said condensers being aligned in a plane parallel to said axial direction, first resistance means external to said column and interconnecting the corresponding plates in one of said sets, second resistance means interconnecting the corresponding plates in the other of said sets whereby said condensers are connected in parallel relation, spark gap means external to said column and arranged to connect said condensers in series relation, and insulating partitions within said column separating said condensers.

3. An impulse generator adapted for energization by a direct-current source, said generator comprising an insulating column, a plurality of 65 condensers each constituted by a pair of parallel plates, said condensers being colinearly arranged at spaced positions in the axial direction within said column, each set of corresponding plates of said condensers being aligned in a plane parallel to said axial direction, first resistance means

external to said column interconnecting the corresponding plates in one of said sets, second resistance means interconnecting the corresponding plates in the other of said sets whereby said condensers are connected in parallel relation, and spark gap means external to said column and arranged to connect said condensers in series relation, said column being defined by a plurality of cup-shaped casings of insulation material coupled together in stacked relation, each condenser being disposed in a respective casing.

4. An impulse generator adapted for energization by a direct-current source, said generator comprising an insulating column defined by a plurality of cup-shaped casings coupled together in stacked relation, each casing being provided with an outwardly projecting flange at one end thereof, a plurality of condensers each constituted by a pair of parallel plates and disposed within a respective casing of said column, said condensers being colinearly arranged at spaced positions in the axial direction of said column, each set of corresponding plates of said condensers being aligned in a plane parallel to said axial direction, first resistance means external to said column interconnecting the corresponding plates in one of said sets, second resistance means interconnecting the corresponding plates in the other of said sets whereby said condensers are connected in parallel relation, and a plurality of spark gaps each positioned external to said

column and interposed between succeeding flanges of said casings, said spark gaps being arranged to connect said condensers in series relation.

5. An arrangement, as set forth in claim 4, wherein said first resistance means is constituted by a plurality of resistors each mounted between the succeeding flanges of said casings on one side of said column, and said second resistance means is constituted by a plurality of resistors each mounted between the succeeding flanges on the opposing side of said column.

6. An arrangement, as set forth in claim 4, wherein each casing at the flange end thereof is internally threaded and at the other end thereof is externally threaded whereby said casings defining the column are threadably intercoupled.
